DISPLAY CONTAINER

Ralph C. C. Nourse, William J. Klein, and Albert L. Dandurand, Manchester, Conn., assignors to Folding Boxes, Incorporated, a corporation of Connecticut

Application January 4, 1940, Serial No. 312,368

11 Claims. (Cl. 248—174)

This invention relates to the general class of display containers which are of the type constructed to be shipped or stored in flat or semifolded condition, and which may be readily manipulated to be arranged in operative position. The invention relates further to a specific type of such devices which are characterized by the use of but a single blank of foldable material.

It is among the primary objects of the invention to provide a display container of the above type which is novel, simple and efficient, having structural features which render it economical in manufacture, sturdy and durable in use and simple in manipulation.

Another primary object of the invention is to provide, in a display container of the type referred to, for the maximum of merchandise capacity and display surface with the minimum of material. This is accomplished in the present invention without sacrifice of strength, durability, ease of manipulation or grace of design.

A further important object is to provide a display container, the blank of which may not only be shipped or stored in flat condition, but which may also be shipped or stored in semifolded condition with the merchandise in its container.

It is among the more specific objects of the invention to provide a device of the character set forth which provides for the combination with a merchandise container of a display card integrally formed therewith and designed to provide a full length display surface unencumbered by the overlapping or hiding of its surface by the merchandise container thereof.

Another object is to provide a display container which when in operative display position will act to support itself in such position without requiring the use of either separate or attached supports, braces, easels, or the like.

A still further object is to provide a display container formed from a blank so cut and scored as to provide for the formation of the walls of a merchandise container pocket as an automatic consequence of the folding by which means excessive or complicated manipulation is avoided.

Numerous other objects, features and advantages of the present invention will be apparent from a consideration of the following specification when considered in connection with the accompanying drawing in which:

Figure 1 is a front elevation of one preferred form of the invention shown in fully folded and extended position with the merchandise pockets formed and ready to receive merchandise;

Figure 2 is a plan view of the blank before folding;

Figure 3 is a section taken on line 3—3 of Figure 1, looking in the direction of the arrows;

Figure 4 is a section taken on line 4—4 of Figure 1, looking in the direction of the arrow;

Figure 5 is a top plan view of the device in self supporting display position; and

Figure 6 is a top plan view of the device in shipping or storage position with the pockets formed to receive merchandise.

It will be understood that that form of the invention here shown by way of illustration is only one of the many forms which may embody the present inventive concept. For instance, while there is here illustrated and described a central display surface having side extensions forming a pair of pocket forming wings the invention is in no wise so limited. In some instances only a single pocket forming wing may be used or the arrangement may provide either one or a pair of pockets without the display surface. Obviously, the shape and design here shown may be widely departed from.

In brief, it may be said that the present embodiment of the inventive concept depicts one of the many applications of the general theme of the invention which resides in the provision of a surface having a pair of spaced, preferable

parallel, fold lines which extend from opposite sides of a through cut. This arrangement provides upon folding for a division of the surface at the fold line whereby one area will form a front and one side wall of a pocket, while the other area will form an extension of the back and an extension of the other side wall of the same pocket. When as in the preferred form of the invention this new arrangement is coupled with an uncut back sheet (here shown as formed

by a reverse folding of a wing of the cut surface) which is folded in alignment with the extension forming area of the cut surface, then the back and one side wall of the pocket are formed by the back sheet and the extension acts to reinforce the back and side.

Referring now to the drawing which presents one preferred embodiment of the invention, the numeral 10 indicates the central display sheet from which extend the pocket forming wings.

As more clearly shown in Figure 2 the finished product is formed from a single blank of material each wing including a panel P foldable as a unit with respect to the central sheet 10 to lie thereagainst if it is desired, to ship or store the blank in partially folded position. The fold line

of the panel **P** with respect to sheet **10**, however, is joined by a through cut **11** extending across the panel **P** and dividing this fold line into an upper section **12** and a lower section **13**. The through cut **11** also divides the panel into an upper and lower area, the upper area being traversed vertically by a fold line **14** to divide the upper area into surfaces **15** and **16** while the lower area is similarly traversed by a fold line **17** dividing the lower area of panel **P** into surfaces **18** and **19**. The bottom of the pocket is preferably formed by a bottom wing **20** having a securing flap **21** and one end of the bottom closure assembly includes a tab **22**, the wing **20**, flap **21** and tab **22** being formed integral with the panel **P** and foldable with respect thereto as indicated by the fold lines **23**, **24** and **25** respectively.

Each wing also includes a pocket back forming surface **27** foldable with respect to panel **P** along the upper fold line **28** and lower fold line **29** which lines, like lines **12** and **13**, are continuations one of the other, but are joined by the through cut **11**.

The outer edge of each wing terminates in a pocket side forming panel **30** having a bottom end closure tab **31** and an end securing tab **32**, fold lines **33** separates the panel **30** from surface **27**, fold line **34** joins tab **31** with panel **30** and fold line **35** joins securing tab **32** with panel **30**.

In the construction here shown, it will be seen that a decorative effect is provided by an aperture **40** formed in the surface **18** and that a curve in the through cut **11** provides a scalloped effect for the top edge of the pocket. Obviously, other similar artistic effects may be similarly provided. It will also be noted that the configuration of the box is determined by the alignment or spacing of the fold lines **14** and **17**. If such lines are in alignment a square pocket will be formed while the spacing here shown will provide the rectangular shape illustrated. Various spacings may, of course, be resorted to.

In forming the device from the blank shown in Figure 2, the panels are folded back on the divided fold lines **28** and **29** so that the sections **27** and **30** lie behind the sections **15**, **16**, **18** and **19**. The securing tabs **32** are then secured as by gluing to the rear face of the surface **10**. The blank is then ready for shipment or storage and, if desired, the blank may be further folded in various ways to minimize the size, such other folds as may obviously be resorted to and are purely discretionary, form no part of the invention.

With the panels folded back and secured as stated above, the next step in forming the pockets is to fold the doubled panel forwardly along the upper fold line section **14** and the line **33** which lines are in registration with each other when the tab **32** is secured. Such folding will automatically and as a consequence thereof fold the surface **18** forwardly of the surface **10** along the line **13** while surface **19** will fold back along the fold line **17**. Such action will bring about an angular relation between **15** and **18** and a similar angular relation between surfaces **16** and **19**. It will be seen that when the folding extends to a 90° angle, the surface **18** will be parallel and forwardly spaced from the surface **16** and the back surface **27**. The rectangular pocket will thus be formed, surface **19** constituting the outer side wall while surface **30** provides the inner side wall. Surfaces **15** and **16** will constitute upward extension of the inner wall and the back which itself is formed by the surface **70**

5 **27**. Since the extension of the back formed by the surface **16** overlies that portion of the surface **27** which extends above the through cut **11** the amount of material used for surface **27** may be diminished and the surface **16** as well as **15** will act to support and lend rigidity and durability to the assembly.

With the pockets so formed, the entire wing may now be folded along the line **12** so that the wings may stand at an angle to the surface **10** (see Figure 5) thus they will act themselves as a support to retain the whole assembly in vertical display position, for, since in manipulation of this device, the fold lines **33** and **35** coincide with angles formed by fold lines **12** and **14** and since the degree of these angles vary thereby changing the radius which must be covered by the fold lines **33** and **35**, it is preferred that the fold lines **12**, **14**, **33** and **35** be compound or double fold lines formed by slightly spaced parallel scorings thus permitting an amplitude of action which will compensate for changes in radius. Obviously other fold lines may be similarly formed should the manufacturer so desire.

10 **30** **35** As shown in Figure 6 after the pockets have been formed they may be folded flat against the surface **10** thus presenting a compact form in which the device may be stored or shipped with pockets formed and if desired filled with merchandise. Throughout this specification, the term "merchandise" has been used in a more than usual sense, since, of course, it will be understood that the pockets may contain advertising matter, such as, cards or leaflets or the like which is not strictly merchandise.

40 **45** It will be understood that this invention is in no way limited to the specific structure here illustrated and numerous changes, modifications and the full use of equivalents may be resorted to in the practice of this invention without departure from the spirit or scope of the appended claims.

What we claim is:

50 **1**. In a device of the character set forth, a panel having a through cut extending thereacross and a pair of oppositely extending fold lines disposed at an angle to the cut and running from the cut to the ends of said panel, said panel being adapted to be oppositely folded on its fold lines to form two pairs of parallel spaced surfaces.

55 **2**. In a device of the character set forth, a panel defined by fold lines, having a through cut extending thereacross and a pair of oppositely extending fold lines disposed at an angle to the cut and running from the cut to the ends of said panel, said panel being adapted to be oppositely folded on its fold lines to form two pairs of parallel spaced surfaces, a second panel connected to the first by a fold line and foldable into engagement with an adjacent one of said parallel surfaces.

60 **3**. In a device of the character set forth, a panel defined by fold lines along its sides and having a bottom forming wing along the bottom, said panel being formed with a through cut extending across the same and a pair of oppositely extending fold lines disposed at an angle to said cut and running from the cut to the ends of said panel, said panel being adapted to be oppositely folded on its fold lines to form two pairs of parallel spaced surfaces.

70 **75** **4**. In a foldable receptacle forming blank, a panel defined by fold lines, having a through cut extending thereacross and a pair of oppositely extending fold lines disposed at an angle to the cut

and running from the cut to the ends of said panel, said panel being adapted to be oppositely folded on its fold lines to form two pairs of parallel spaced surfaces, and a second panel connected to the side of the first panel by a fold line, said second panel being formed with a fold line therein parallel to the fold lines to the panel which is provided with a cut and foldable into engagement with two of said surfaces to reinforce the same.

5. In a device of the character set forth, a pocket the front and one side wall of which is formed by one portion of a panel defined by fold lines, having a through cut extending thereacross and a pair of oppositely extending fold lines disposed at an angle to the cut and running from the cut to the ends of said panel, said panel being adapted to be oppositely folded on its fold lines to form two pairs of parallel spaced surfaces.

6. In a device of the character described, a 20 doubled portion of material forming a pair of panels, one of which has a through cut extending thereacross and a pair of oppositely extending fold lines disposed at an angle to said cut and running from the cut to the ends of said panel, 25 the panel in which said cut is formed being adapted to be oppositely folded on its fold lines to form two pairs of parallel spaced surfaces constituting a pocket and the other panel having a bottom closure element for said pocket formed thereon as an integral wing extending from said other panel.

7. In a device of the character described, a doubled portion of material forming a pair of panels, one of which has a through cut extending thereacross and a pair of oppositely extending fold lines disposed at an angle to said cut and running from the cut to the ends of said panel, the panel in which said cut is formed being adapted to be oppositely folded on its fold lines to form two pairs of parallel spaced surfaces constituting a pocket while the other panel is foldable with one of said fold lines to form a continuation of two of said surfaces.

8. In a device of the character set forth, a blank including a panel having a through cut dividing the panel in upper and lower sections each of which is traversed by a fold line running from

the cut to the end of the panel, second panel contiguous with said first panel and having a fold line which, when the panels are folded against one another is in registration with one of the fold lines of one of said sections whereby opposite folding of the fold lines of one of the sections and folding of the second panel with the folding of one section will form a pocket by the cooperation of one section and the second panel.

10. In a device of the character set forth, a blank including a panel having a through cut dividing the panel into upper and lower sections each of which is traversed by a fold line running from the cut to the end of the panel, second panel 15 contiguous with said first panel and having a fold line which, when the panels are folded against one another is in registration with one of the fold lines of one of the sections whereby opposite folding of the fold lines of one of the sections and folding of the second panel with the folding of one section will form a pocket by the cooperation of one section and the second panel and closure elements for the bottom of said pocket formed as integral wings projecting from the edges of said panels and connected thereto by fold lines extending parallel to said cut.

10. In a device of the character set forth, a wing including a pair of panels folded in parallel contact, one of which has a through cut dividing it into two portions, one portion and the other panel being foldable together to form a section of L shaped configuration while the other section is oppositely foldable to form an opposite joined L shaped section whereby said sections unite to form a pocket.

35 11. In a device of the character set forth, a wing including a pair of panels folded in parallel contact, one of which has a through cut dividing it into two portions, one portion and the other panel being foldable together to form a section of L shaped configuration while the other section is oppositely foldable to form an opposite joined L shaped section whereby said sections unite to form a pocket, said panels having attached wings foldable to form a bottom closure for said pocket.
